CLAIM

The ornamental design for a circular satseconds indicator and a triangular saturation pattern detection indicator for a patient monitor display panel, as shown and described.

DESCRIPTION

FIG. 1 is a perspective view of a circular satseconds indicator and a triangular saturation pattern detection indicator for a patient monitor display panel, shown in the environment of a partially shown pulse oximetry monitor;

FIG. 2 is a front view thereof, where the circular indicator is about three quarters full and the triangular indicator is about three quarters full;

FIG. 3 is a front view thereof, shown in the environment of a multi-parameter monitor; and,

FIG. 4 is a front view thereof, shown in the environment of a pulse oximetry monitor, where the circular indicator is about three quarters full and the triangular indicator is about half full.

The broken lines showing the display panel and portions of the patient monitor are for the purpose of illustrating unclaimed portions and form no part of the claimed design.
